ELECTRON DISCHARGE DEVICE

Clifford E. Fay, South Orange, N. J., assignor to
 Bell Telephone Laboratories, Incorporated, New
 York, N. Y., a corporation of New York

Application May 12, 1933, Serial No. 670,692

9 Claims. (Cl. 250—27.5)

This invention relates to electron discharge devices and more particularly to such devices adapted for the generation of ultra-high frequency oscillations and commonly known in the art as Barkhausen oscillators.

In Barkhausen oscillators, the electron receiving or output electrode is perforate in structure and of necessity is of relatively small area. The temperatures which this electrode can withstand safely therefore are relatively low and as a result the power capacity of devices of this type is limited.

One object of this invention is to dissipate heat from an electrode in an electron discharge device and thereby to increase the power capacity of the device.

Another object of this invention is to improve the operating characteristics and efficiency of Barkhausen oscillators.

In one embodiment of this invention, an electron discharge device comprises a cylindrical electrode, a cathode and an output or grid electrode within the cylindrical electrode and extending beyond the ends thereof.

The cathode comprises a linear filament supported at its ends and disposed coaxially within the cylindrical electrode. The output electrode comprises a pair of spaced tubular members positioned beyond the ends of the cylindrical electrode and a plurality of parallel linear wires extending between the tubular members and disposed in a cylindrical boundary coaxial with the cathode and the cylindrical electrode.

In accordance with a feature of this invention, the parameters of the electrodes are correlated so that a relatively high operating efficiency is obtained.

In accordance with another feature of this invention, heat radiating members are associated with the output electrode in order to dissipate the heat therefrom. In one form the members may comprise metallic discs of relatively large area, mounted on the tubular members of the output electrode assembly.

In accordance with a further feature of this invention, a plurality of imperforate tubular members are mounted on the cathode and surround the portions thereof extending beyond the ends of the cylindrical electrode. These members serve to confine the electron flow to a desired path and prevent the flow of electrons to the tubular members in the output electrode assembly.

The invention and the various features thereof will be understood more clearly and fully from

the following detailed description with reference to the accompanying drawing in which:

Fig. 1 is a perspective view of an electron discharge device illustrative of this invention, with portions of the enclosing vessel and of the electrode structures broken away to show details of construction more clearly;

Fig. 2 is an enlarged end view of the electrode assembly showing the relative disposition of the cathode and the output electrode, filament leads and the heat radiating members for the output electrode; and

Fig. 3 is a side view in cross-section showing details of the cathode and output electrode assemblies.

Referring to the drawing, the device shown is of the type adapted for the generation of ultra-high frequency oscillations and commonly known as a Barkhausen oscillator. It comprises an evacuated enclosing vessel 10 having a reentrant stem 11 which terminates in a press 12. A pair of bent or substantially inverted L-shaped wires 13 are embedded at one end in the press 12 and have secured thereto a pair of parallel metallic rods or uprights 14. A single linear filament 15 of tantalum, tungsten or other material having good electron emitting characteristics, is secured at its ends to the rods or uprights 14 and serves as the cathode of the device. The heating current for the cathode may be supplied through leading-in conductors 16 connected to the wires 13.

A bent wire 17 is embedded at one end in the press 12 and at the other end in an insulating bead 18, the wire 17 being disposed in a plane at substantially right angles to the plane of the wires 13. A metallic ribbon 19 is secured at one end to a rod 20 embedded in the insulating bead 18, and at the other end to another rod 21 sealed in the end of the enclosing vessel 10 as shown at 22. The ribbon 19 is preferably flexible and bowed to allow longitudinal expansion and contraction of the rods 20 and 21 with temperature variations.

A cylindrical electrode 23 having a flange 24 is supported from rigid L-shaped wires 25 secured, as by welding, to the rod 20 and to the flange 24 and a reinforcing rod or wire 41 on the flange. The electrode 23 may be of sheet molybdenum, the surfaces of which are roughened by carborundum blasting to increase the heat radiation therefrom, and is disposed about and spaced coaxially with respect to the filament 15.

A bent wire 26 is embedded at one end in the

press 13 and carries an insulating bead 27. A bowed flexible metallic ribbon 28, similar to the ribbon 19 is connected between a rod 29 embedded in the insulating bead 27 and a rod 30 sealed in the enclosing vessel 10 as shown at 31. A U-shaped wire support 32 is secured to the rod 29 and is rigidly held in position by braces or rods 33 secured thereto and to the rod 29.

An output or grid electrode assembly is carried by the support 32 and comprises a pair of cylindrical metallic collars 34 connected to the arms of the support 32 by short rigid wires 35, only one of which is shown in Fig. 1. The collars 34 encircle the ends of the filament 15 and have secured thereto a plurality of equally spaced parallel wires 36 which may be of tungsten and are disposed parallel to the filament 15 and arranged in a cylindrical boundary coaxial with the filament.

This construction provides a substantially non-inductive electrode and inasmuch as the wires 36 are symmetrical at all points with respect to the filament 15 a uniform field between the filament and the wires is obtained with a resultant uniformity of electronic action. Furthermore, this construction facilitates the conduction of heat from the center portion of the wires 36 to the ends thereof and thereby enables the dissipation of the heat by radiation.

In devices of the type described, the electrode 23 is usually operated at zero potential, or at a slightly negative potential with respect to the filament 15 and the grid or output electrode is operated at a high positive potential, for example, several hundred volts, with respect to the filament. The grid or output electrode has a very small surface area and is spaced very close to the filament. For example, in a device capable of producing oscillations of a wave length of the order of 40 centimeters, the grid or output electrode may have an inner diameter of 0.156 inch, the grid wires being 0.010 inch in diameter, and the filament may be 0.008 inch in diameter. During the operation of the device, the grid becomes heated and the power output of the device is therefore limited by the temperatures which the grid electrode can safely withstand. In order to increase the power capacity of the device, means are provided, in accordance with a feature of this invention, to dissipate the heat from the grid electrode. For this purpose, a pair of vanes or annular discs 37 of relatively large area, and of a material having good heat radiating characteristics, for example, molybdenum or nickel roughened by carborundum blasting, are disposed adjacent the ends of the grid wires 36 and are thermally coupled thereto. The disc 37 may be disposed in contact with the collars 34 and may be connected to the collars by a plurality of bent wires 38 of good thermal conductivity.

In order to insure uniform operating characteristics and a relatively high operating efficiency, the collars 34 are preferably disposed beyond the ends of the electrode 23. To substantially prevent the flow of electrons to the collars and thereby to confine the electrons emitted from the filament 15 to paths embracing the wires 36 of the output electrode, the end portions of the filament within the collars 34 may be surrounded by tubular sleeves 39 of nickel or the like, secured to the uprights 14 by tabs 40.

The efficiency of devices of the Barkhausen oscillator type is dependent to a material extent upon the relative diameters of the grid electrode and the electrode 23. Particularly good results

are obtained with devices in which the diameters of the electrode 23 and of the output or grid electrode are in the ratio of substantially 3.6 to 1. Variations of plus or minus 10% in this ratio, that is, the ratios being between approximately 3.2 to 1 and 4.0 to 1, have been found to be not particularly detrimental.

Although a specific embodiment of this invention has been shown and described, it is to be understood, of course, that many modifications may be made therein without departing from the scope and spirit of this invention as defined in the appended claims.

What is claimed is:

1. An electrode assembly for electron discharge devices, comprising a pair of spaced metallic cylindrical members, a plurality of wires extending between and secured at their ends to said members, said wires constituting an electrode, metallic discs of relatively large area adjacent said cylindrical members, and a plurality of members of high thermal conductivity connecting said discs to said cylindrical members.

2. A Barkhausen oscillator comprising a cathode, a cylindrical output electrode encircling said cathode, and a cylindrical electrode encircling said output electrode and disposed coaxially therewith, the ratio of the diameters of said second cylindrical electrode and said output electrode being between 3.2 to 1 and 4.0 to 1.

3. A Barkhausen oscillator comprising a cathode, a cylindrical output electrode encircling said cathode, and a cylindrical electrode encircling said output electrode and disposed coaxially therewith, the ratio of the diameters of said second cylindrical electrode and said output electrode being substantially 3.6 to 1.

4. A Barkhausen oscillator comprising a cathode, a cylindrical electrode encircling said cathode and disposed coaxially therewith, and an output electrode intermediate said cathode and said cylindrical electrode including a plurality of parallel wires mounted in a boundary coaxial with said cathode, the ratio of the diameters of said cylindrical electrode and said boundary being substantially 3.6 to 1.

5. An electron discharge device comprising an enclosing vessel having a stem, a plurality of wires extending from said stem, a cathode mounted on said wires, a plurality of supporting members embedded in said stem at one end and anchored at the other end to said enclosing vessel at points remote from said stem, each of said supporting members having a flexible portion, an electrode carried by one of said members and encircling said cathode, and another electrode carried by another of said members encircling said first electrode and coaxially disposed therewith.

6. An electron discharge device comprising an enclosing vessel having a stem, a plurality of supports extending from said stem, a filament extending between two of said supports, a cylindrical electrode carried by another of said supports, and encircling said filament, a pair of tubular members carried by another of said supports and encircling said filament, and an electrode extending between and secured to said tubular members.

7. A Barkhausen oscillator comprising an enclosing vessel having a stem, a cylindrical electrode supported from said stem, a linear filament disposed coaxially within said electrode and having portions extending beyond the ends thereof, sleeve members encircling said portions, a support extending from said stem, a plurality of

tubular members carried by said support and encircling said sleeve members, and a plurality of wires extending between and secured to said tubular members, said wires being disposed parallel to one another and to said filament and mounted in a cylindrical boundary coaxial with said filament.

8. An electron discharge device comprising an enclosing vessel having a stem, a plurality of supports extending from said stem, a filament extending between two of said supports, a cylindrical electrode carried by another of said supports, a pair of spaced metallic cylindrical members carried by another of said supports, a plurality of wires extending between and secured at their ends to said members, said wires constituting an electrode, and metallic vanes of relatively large area mounted on said members.

9. A Barkhausen oscillator comprising an enclosing vessel having a stem, a cylindrical electrode supported from said stem, a linear filament disposed coaxially within said electrode and having portions extending beyond the ends thereof, sleeve members encircling said portions, a support extending from said stem, a plurality of tubular members carried by said support and encircling said sleeve members, a plurality of wires extending between and secured to said tubular members, said wires being disposed parallel to one another and to said filament and mounted in a cylindrical boundary coaxial with said filament, metallic discs of relatively large area adjacent said tubular members, and a plurality of members of high thermal conductivity connecting said discs to said cylindrical members.
